US00D750599S

(12) **United States Design Patent**
Miki et al.

(10) **Patent No.:** **US D750,599 S**
(45) **Date of Patent:** **** Mar. 1, 2016**

(54) **PORT FOR AUDIO EQUIPMENT**

(71) Applicant: **Yamaha Corporation**, Shizuoka (JP)

(72) Inventors: **Akira Miki**, Shizuoka (JP); **Hirofumi Onitsuka**, Shizuoka (JP)

(73) Assignee: **Yamaha Corporation**, Shizuoka (JP)

(**) Term: **15 Years**

(21) Appl. No.: **29/536,147**

(22) Filed: **Aug. 13, 2015**

Related U.S. Application Data

(62) Division of application No. 29/476,340, filed on Dec. 12, 2013.
